UNITED STATES PATENT OFFICE.

LOUIS A. HAWTHORNE, OF HILLSIDE, NEW JERSEY, ASSIGNOR TO ANCHOR POST FENCE COMPANY, OF GARWOOD, NEW JERSEY, A CORPORATION OF NEW JERSEY.

GATE HINGE.

Application filed May 7, 1927. Serial No. 189,474.

This invention relates to hinges for gates and the like, having reference more especially to hinges for gates of the class in which heavy wire fabric is supported by and within 5 a rectangular frame structure of metal work.

An object of my invention is to provide a strong and reliable hinge construction whereof the relatively movable members can be readily associated and attached to the gate 10 frame and the adjacent supporting post, respectively.

Another object of my invention is to provide a hinge connection wherein the pintle or pivot between the relatively movable 15 members can be nicely adjusted, within limits, in relation to the gate post in order to ensure the correct hanging or positioning of the gate.

With these and other objects in view my 20 invention comprises novel features of construction and combinations of parts which will be hereinafter described and claimed.

In the drawings—

Figure 1 is a sectional plan of the upper 25 portion of a gate equipped with a hinge embodying my invention.

Fig. 2 is a front elevation of the structure shown in Fig. 1.

Fig. 3 is a vertical section through the 30 hinge, as on the line 3—3 of Fig. 1.

Figs. 4 and 5 are transverse sections, as on the line 4—4 of Fig. 2, showing different positions of adjustment of the pintle and its eccentric bearing.

Referring to the drawings, 10 designates 35 a portion of the upper horizontal rail of a gate frame, and 11 designates a portion of one of the vertical members thereof, it being understood that the top and bottom rails are or may be of the same construction, and 40 that the vertical members at the respective ends of the frame also are or may be of the same construction.

12 designates interlooped or interwoven 45 open wire fabric, of the "chain link" type, which is secured to and held under tension between the respective members of the frame.

The particular gate frame construction herein illustrated is similar to that described 50 in Letters Patent of the United States No. 1,283,359 dated October 29, 1918, wherein the rail comprises a stout metal tube, and each end member comprises two connected channel bars arranged back to back and in spaced 55 relation to each other, the respective pairs

of bars having affixed thereto at or near each end two exteriorly arranged parallel cheek members, 13, which extend horizontally and embrace the adjacent rail.

The upper hinge connection only is illustrated as the lower connection is or may be a duplicate thereof. The hinge connection comprises two complementary elements, A, B, the element A which is formed of two double jaw members being secured to the adjacent supporting post 14, and the element B being affixed to the adjacent end of the gate frame.

The element A comprises two counterpart 70 members 15 having internal semi-circular conformation at one end, which members when secured together provide a circular clamping opening therebetween. Extending from the members 15 are arms 16, which are adapted to embrace the gate post. The 75 members 15 are secured together and at the same time the arms 16 are firmly clamped to the post by means of a diagonally disposed through bolt 17 which extends through the members adjacent the bases of the arms. In 80 the present instance these arms are angularly related and are provided at their outer or free ends with retaining lips 18, so that the arms can be readily applied and clamped to the sides of a tubular post 14 of square cross- 85 section, as shown.

Fitted in the circular opening afforded by the members 15 is a cylindrical member 19, the ends of which extend exteriorly of the opening and are formed with polygonal heads 90 20 to which a wrench or similar tool can be readily applied. The member 19 is formed with a bore 21 eccentric to its longitudinal axis, and hence by loosening the bolt 17, and turning the member 19 about its axis, the 95 bore 21 can be adjusted to any desired position about the axis, and then by tightening the said bolt, the member 19 can be effectually secured in the position of adjustment.

The element B comprises a base or block 100 portion 22 which is fitted snugly between the outwardly projecting ends of the cheek members 13 and is formed at one side with a leg 23 which extends between the vertical frame bars 11 and into the open end of the rail 10, 105 within which latter it is secured by means of a transverse bolt 24 passing through the cheek members, the rail and the leg 23.

The opposite side of the block 22 is provided with an outwardly and rearwardly ex- 110

tending arm 25 the free end of which is formed with a perforation 26 that registers with the eccentric bore of the cylindrical member, and a pintle 27 passing through such 5 perforation and bore hingedly connects the two elements A, B.

From the foregoing it will be seen that my invention provides a simple and efficient hinge member, the axis of the pintle whereof 10 can be adjusted with ease and facility, to insure the correct hanging of the gate; that is to say, by varying the position of the pintle the gate can be set with extreme nicety toward or from the post, as the size of the gate 15 opening may require, or the pintle of one hinge may be adjusted with relation to that of the other hinge in order to secure the efficient co-operative relation of the two hinges.

A hinge embodying my invention is simple and efficient, and the parts thereof, which 20 are relatively few, can be readily assembled and applied to the gate and its support.

It is to be understood that my invention is not limited to the details of construction herein disclosed as the same may be modified within 25 the principle of the invention and the scope of the appended claims.

I claim—

1. A gate hinge comprising two elements 30 whereof one is composed of two parts with an opening therebetween, an eccentric member mounted for rotative adjustment in said opening, means for clamping the said eccentric member between said parts, and a pivotal connection between the other element 35 and the eccentric member.

2. A gate hinge comprising two elements whereof one is composed of two parts with

an opening therebetween, an eccentric member mounted for rotative adjustment in said 40 opening, a bolt adjustably clamping the said parts against the eccentric member, and a pivotal connection between the other element and the eccentric member.

3. A gate hinge comprising two elements, 45 one of which is composed of two parts having their opposing faces formed to provide an opening therebetween and having also two extending clamping arms adapted to embrace a post, an eccentric member mounted for rotative adjustment in said opening, a bolt adjustably connecting the said parts to clamp the eccentric member in adjusted position and also to clamp the arms against the post, and a pivotal connection between the other element 50 and the eccentric member.

4. A gate hinge having two elements whereof one includes clamping means for engaging a post and the other includes clamping 55 means for engaging a gate, a connection for the two elements comprising a pintle and a rotative adjusting member having an axis of rotation eccentric to the axis of the pintle, one of the said elements being formed of two parts with a circular opening therebetween 60 for the reception of the rotative member, and a bolt extending through said parts between the circular opening and the adjacent post-clamping means and operative to clamp the latter to the post and also to clamp the rotative member by and between the walls of the circular opening.

Signed at Garwood, in the county of Union and State of New Jersey, this 2nd day of May, A. D. 1927.

LOUIS A. HAWTHORNE.
